SIGNALING LAMP

Arthur Cyril Webb Aldis, Sparkhill, Birmingham,
England, assignor to Aldis Brothers Limited,
Sparkhill, Birmingham, England

Application January 8, 1943, Serial No. 471,722
In Great Britain October 22, 1941

7 Claims. (Cl. 88—112)

This invention relates to signaling lamps for naval, military and other like uses, and of the kind adapted to emit light flashes of different colours. The object of the invention is to provide an improved signaling lamp or lamp attachment enabling a greater amount of the light from the source to be used than is obtained in lamps of ordinary construction, and also enabling the sequence of the different coloured flashes to be readily varied.

The invention comprises in combination a plurality of louvre-like screens adapted to transmit light of different colours and arranged one behind another, and means for actuating the screens.

In the accompanying sheets of explanatory drawings—

Figure 1 is a sectional side elevation, Figure 1a a sectional plan (taken on the line A—B of Figure 1), Figure 2 a rear elevation, and Figure 3 a front elevation, of a signaling lamp attachment embodying the invention.

Figure 4 is a detail sectional view taken on the line 4—4 of Figure 1.

Figure 5 is a section on the line 5—5 of Figure 1.

Figure 6 is a developed view of a controlling gate shown in Figures 1 to 4.

In Figure 1 a indicates a signaling lamp which contains a light source b and a lens mirror c, and to the front of which can be secured the attachment embodying the invention. This attachment consists of a rectangular sheet metal or other casing d containing three louvre-like screens e whereby the required different coloured light can be transmitted, and carrying means as hereinafter described for actuating movable parts of the screens, the front and rear ends of the casing being formed with circular openings f through which can pass the beam of light from the lamp a. The rear of the casing d is formed with key-hole slots g which, by engagement with headed studs h on the front of the lamp a, serve to attach the casing to the lamp front, the casing being held in position by the engagement of one of the stud heads with a detent in the form of a spring blade i on the inner side of the rear of the casing. On the centre of the rear of the casing d is mounted a dished or cup-shaped baffle j for preventing emission from the lamp a of direct light from the source b, the baffle being carried by a metal strip k which extends diametrically across the opening f in the rear of the casing. The front end of the casing d is provided with headed studs m whereby a framed flat or other glass piece (which may be the ordinary 55

front glass of the lamp a) can be secured to the front of the casing.

Each of the screens e comprises a plurality of rectangular strips n adapted to transmit light of the required colours, and a supporting frame o across which the strips extend, the sides of the frame being detachably secured to the adjacent sides of the casing d. The strips n of each screen e are secured at both ends of lever-like clips or holders p, the latter being pivoted at q to the adjacent sides of the corresponding frame o, and at r to interconnecting links s, one such link being provided at each side of each frame and serving to interconnect the adjacent clips or holders. Arranged transversely across and supported by the lower end of each frame o is a rotatable spindle t which is situated parallel to the strips n, and which is provided at its ends with short radial arms u, the latter being connected to the adjacent links s so that the corresponding strips can be moved from a closed position to an open position by appropriate movement of the spindle. In the closed position of the strips n they lie in substantially the same plane with their adjacent longitudinal edges overlapping. In the open position they lie at right angles to that plane, and when in this position they offer a minimum of obstruction to light as they are made from thin material. Return of the strips n to the closed position may be effected by gravity with or without the assistance of any convenient springs, such as those indicated by v in Figure 5, which may be connected to the links s, and which serve to prevent accidental sticking of the strips in any intermediate position.

I may employ any desired number of screens e as above described, but for the purpose of elucidating the invention we have shown in the drawings a combination of three screens capable of giving red, green, and white or uncoloured flashes, the red screen being situated adjacent to the front of the casing d, the green screen near the centre of the casing, and the white screen near the rear of the casing. The strips of the red screen are made from red translucent material, and those of the green screen from green translucent material. The strips of the white screen may be made from clear or frosted material, but as the light transmission loss associated with a white screen is usually much less than that associated with a coloured screen, and as in consequence a white screen of similar character to the coloured screens would give a relatively brighter flash, I find it convenient to make the strips of the white screen from thin metal formed

with perforations *w*, the area exposed by the perforations being sufficient to transmit the required amount of light. As the colours red and green are complementary, a practically opaque effect is obtained when the red and green screens are closed at the same time, and it is therefore unnecessary to employ an additional opaque screen for occulting the light between successive flashes, though such a screen may be used if desired. Alternatively, and where it is of paramount importance that no glimmer of light should be emitted between the flashes, I may employ a series of overlapping opaque and imperforate louvres and when an uncoloured flash is desired these are only partially opened, the degree to which they are opened being adjusted so as to give to the white flash a similar intensity to that provided to the eye of the observer by a coloured flash. When sending a coloured flash this series of opaque louvres are fully opened so as to provide the full intensity of the signalling lamp for transmission as a coloured flash and only a fraction of it for an uncoloured flash.

As previously indicated the three screens *e* above described are mounted one behind another in the casing *d* which is adapted to be mounted on the front of the housing of a separate signalling lamp as *a*. Alternatively the casing may have a lamp housing combined with it. But in either case the source of light as *b* (which is usually an incandescent filament bulb) may have the above-mentioned lens mirror *c* behind it or a lens in front of it or other optical means for projecting a powerful beam of limited divergence. In cases where a beam of moderate divergence is required it may be convenient to obscure the direct light from the source by the baffle *j* above described. But in those cases where it is desired to send out a beam of wide divergence I employ a front glazing having parallel cylindrical lenses moulded on one surface to give the desired divergence in any selected direction, or I employ a front glazing having crossed cylinders on the back and front surfaces to give any desired divergences in all directions. This enables me to avoid the slight tinting of marginal portions of a wide angle beam which would otherwise occur.

For actuating the screen-strips *n* I employ a combination of three spring loaded push rods *x*, these being situated within the casing *d* in parallel relationship with each other and at right angles to the operating spindles *t*.

A simple, though not the most convenient, mode of connecting the rods *x* to the strips *n* would be to provide each of the rods with a toothed rack for engaging a pinion on each of two of the operating spindles. Thus, for example, one of the rods would serve to actuate the white and green screens. Inward movement of this rod would open the white and green screens, leaving the red one closed and so causing a red light to be shown. In like manner another rod would serve to cause a white light to be shown and the third rod a green light. On releasing any rod it would be returned by its spring, causing the two screens associated with it to be reclosed. With the lamp not in operation all screens would be closed.

The above described connecting means though simple has the disadvantage of necessitating the signaller manipulating the push rods *x* in the appropriate sequence. It is obviously preferable to be able to operate the rods always in a predetermined sequence, and to enable this condi-

tion to be satisfied with any combination of differently coloured successive flashes. I make each push rod *x* rotatable about its longitudinal axis as well as slidable along that axis. Also I provide on each rod *x* three gapped racks *y*, these being arranged so that they can be caused to engage any two or three pinions or toothed segments *z* provided respectively on the spindles *t*. To determine the pinions or toothed segments *z* to be engaged, I employ three bushes *2* which extend through and are rotatably supported by the rear end of the casing *d*, and which respectively accommodate and serve as bearings for the adjacent ends of the rods *x*, these ends of the rods and the interiors of the bushes being of complementary non-circular cross section so that the rods and bushes are capable of independent axial movements but are incapable of independent rotational movements. The bushes *2* are closed at their outer ends to form abutments for the adjacent ends of compression springs as *3* which are mounted in axial bores as *4* in the rear ends of the rods *x*, and which at their other ends abut against the inner ends of the said bores, the arrangement being such that the springs serve to hold the rods and bushes in their normal positions. At their inner ends the bushes *2* are formed with flanges *5* which bear against the inner surface of the rear end of the casing *d*, and which are each provided with a pin *6*. Each of these pins *6* is adapted to engage any one of a plurality of holes *7* in the rear end of the casing *d*. By exerting pressure on the outer end of any one of the bushes *2*, the signaller can move this bush axially against the action of the associated spring *3* to disengage the pin *6* on the bush from any one of the corresponding holes *7*, whereupon the signaller can rotate the bush to a position in which it can be caused by the action of the spring to engage any other of the holes *7*. Such rotational adjusting movement of any one of the bushes *2* is accompanied by corresponding movement of the associated push rod *x*, and serves to determine which of the corresponding pinions or toothed segments *z* are engaged by the gapped racks *y* on that push rod when the latter is moved axially against the action of its loading spring *3*.

The selective arrangement above described enables twenty-seven different combinations of flashes to be obtained, and after the bushes *2* have been set to the desired positions it is only necessary for the signaller to operate the push rods *x* in the order of their arrangement; that is to say the signaller always operates the rods in the one sequence, but the sequence of the colours in the flashes is determined by the setting of the bushes. After being operated by the signaller each push rod *x* is returned by its loading spring *3*.

When the push rods *x* are in their normal positions they project from the front end of the casing *d* under the action of the springs *3*, and the gapped racks *y* on the push rods are clear of the corresponding pinions or toothed segments *z*. Consequently all three screens *e* are closed. Upon any push rod *x* being moved against the action of its loading spring *3* to the position shown in Figure 1, the appropriate pinions or toothed segments *z* are actuated to open two of the screens *e*.

Preferably and as shown I provide in the rear end of the casing *d* four of the above mentioned holes *7* for alternative engagement by the pin *6* on each bush *2*. One of these holes serve to

hold the corresponding bush in a position in which the associated push rod x is ineffective, that is to say, in which the gapped racks y on that rod have no effect on any of the pinions or toothed segments z , when the rod is actuated by the signaller. The other holes 7 serve as previously indicated to determine the pinions or toothed segments z engaged.

To simplify further the manipulation of the screens above described, I may employ a single trigger for actuating the push rods x it being then only necessary while signaling for the signaller to give successive movements to the one trigger. This condition can be satisfied in a variety of ways one of which will now be described.

As shown there is mounted within the casing d at a position centrally below the push rods x , another slideable and rotatable rod 8 which is situated parallel to the push rods, and which projects through the front end of the casing d . At its outer end the rod 8 carries a radial arm 9 which by appropriate movements of the rod can serve to actuate the push rods x in the proper sequence.

Contact of the arm 9 with a stop which may be formed by the front of the casing d determines the extent to which the push rods x can be moved by this arm and a spring 10 surrounding the rod 8 serves to return the latter to an inoperative position after it has been moved to actuate a push rod.

Secured on the rod 8 at a position within the casing d is another radial arm 11 to which is anchored one end of a tension spring 12 tending constantly to move this arm, and consequently the rod and the other arm 9 , in a clockwise direction, the other end of the spring being anchored to the casing. At its outer end the arm 11 carries a pawl 13 which is held by the spring 12 against one face of a gate 14 in the casing, this gate serving to control angular movement of the arm in the manner hereinafter described.

To the underside of the casing d is secured a vertical post-like handle 15 for holding and steadyng the signaling device above described, and at the front of this handle is arranged a trigger 16 whereby axial movement can be imparted to the rod 8 for causing the required flashes to be emitted, the outer end of this rod being loosely encircled by the upper end of the trigger. This trigger has a simple motion of translation in the direction for imparting axial movement to its supporting rod, but is prevented from rotating about the axis of the rod by the engagement of a peg 17 on the trigger with a slot cut or cast in the upper end of the above mentioned handle 15 . In addition to being movable axially by the trigger 16 for actuating the push rods x the rod 8 is constrained to move angularly after each operation of the trigger for enabling the push rods to be operated in a predetermined order and then preventing further operation of the trigger until the rod 8 has been reset. This angular movement of the rod 8 is effected by the spring 12 under the control of the gate 14 , the latter being shown in a developed form in Figure 6. The gate 14 consists of a block of synthetic resin, or other suitable material secured in the front of the casing d at a position slightly above the rod 8 . The underside of this block is shaped to provide a plurality of thin and thick rib-like guide members $18, 19$ arranged in parallel relationship and around a cylindrical surface concentric with the rod 8 . The thin guide

members 18 of which there are three alternate with and lie over the greater part of their length between the thick guide members 19 of which there are two, the spaces between the various guide members being sufficient to accommodate the outer end of the pawl 13 on the arm 11 . When the rod 8 is in its initial position preparatory to causing actuation of the three push rods x in sequence, the pawl 13 is held by the spring 12 tightly against the outer face and near the outer end of the thin guide member 18 shown in the uppermost position in Figure 6. Also the outer end of the arm 9 on the rod 8 is opposite to the outer end of the first push rod x shown at the left hand side of Figure 5. If now the rod 8 is moved axially by the trigger 16 to actuate the first push rod x , the pawl 13 moves along the adjacent thin guide member 18 until it reaches the end of this guide member, whereupon the spring 12 moves the pawl into contact with the adjacent thick guide member 19 . The angular movement thus imparted to the rod 8 is, however, insufficient to move the outer end of the arm 9 out of contact with the outer end of the actuated push rod. During the return axial movement of the rod 8 under the action of the spring 10 , the pawl 13 moves along the above mentioned thick guide member 19 until it reaches the end of this member. The spring 12 now moves the pawl 13 into contact with the second thin guide member 18 , and the angular movement thus imparted to the rod 8 brings the arm 9 into a position in which its outer end is opposite to the outer end of the next push rod x so that this push rod is actuated by the next axial movement imparted to the rod 8 by the trigger 16 . This movement of the rod 8 and its return are accompanied respectively by movements of pawl 13 along the second thin and thick guide members $18, 19$, whereupon the pawl is moved by the spring 12 into contact with the third thin guide member 18 , the angular movement thus imparted to the rod 8 serving to bring the outer end of the arm 9 opposite to the third push rod x . This push rod is therefore actuated by the next axial movement of the rod 8 by the trigger 16 . At the end of the return movement of the rod 8 the pawl 13 is caused by the spring 12 to enter a recess 20 (Figure 6) in the gate 14 and prevent further operation of the trigger 16 until the mechanism is reset.

To reset the mechanism for enabling the push rods x to be again operated in the same sequence as before by successive operative movements of the trigger 16 , the rod 8 is turned against the action of the spring 12 , causing the pawl 13 to ride over the guide members $18, 19$ and re-engage the first guide member. This turning movement of the rod 8 can be effected by the signaller through the agency of a curved or bent arm 21 which extends through a slot in the underside and near the rear end of the casing d . At its inner end this arm 21 is formed on or secured to a hollow boss 22 to which the adjacent end of the rod 8 is slidably but non-rotatably connected, and which serves as an abutment for one end of the spring 10 surrounding the rod. The boss 22 is rotatably supported by a bearing in the form of an angularly adjustable bush 23 which extends through the rear end of the casing d . The bush 23 is formed with a flange 24 which bears against the inner surface of the rear end of the casing d under the action of the spring 10 , and which is provided with a pin 25 adapted to engage any one of three holes 26 in the rear end

of the casing to retain the bush in the desired adjusted position. Also provided on the bush flange 24 is a projection 27 (Figure 5) adapted by contact with an arm 28 (Figure 1) on the boss 22 to serve as an adjustable stop for limiting the angular movement that can be imparted to the rod 8, the arrangement being such that by appropriate adjustment of the stop through the agency of its supporting bush only one, or two, or all three of the push rods 2 may be actuated before movement of the trigger 16 is prevented as above described.

It will be understood that the invention is not limited to the use of three screens as any desired number of screens may be used. Also the invention is not limited to the particular actuating means described as subordinate constructional and mechanical details may be varied to suit different requirements.

It will be apparent from the foregoing description that by my invention I am able to effect a minimum of obstruction to the light emitted from the front of the lamp housing, as the area presented by the open screens to the light is very small, and consequently the greater part of the light emitted from the lamp housing is usefully transmitted through the screen which is in action, excepting the white screen which for the reason mentioned may be purposely designed to obstruct a part of the light emitted by the source.

Having thus described my invention what I claim as new and desire to secure by Letters Patent is:

1. A signaling device having in combination a plurality of louvre-like screens adapted to transmit light of different colours and each comprising a plurality of pivoted light-transmitting members, links connected to said members and actuatable to move said members between closed and open positions, spindles connected to the links so that rotational movement of the spindles serves to actuate the links, and spring-loaded push rods operable by the signaller, the spindles and push rods being provided with interengagable parts whereby sliding movements of the push rods cause rotational movements of the spindles, and thereby cause the links to be actuated for moving the said members into positions in which light of different colours can be transmitted.

2. A signaling device as claimed in claim 1, in which the push rods are rotatably adjustable about their longitudinal axes to determine which of the parts on the spindles are engaged by the parts on the push rods.

3. A signaling device as claimed in claim 1 and having in combination a slidable and rotatable spring-loaded operating rod arranged parallel with the push rods, a radial arm secured on the operating rod and adapted to actuate the push rods in sequence, a trigger mounted on the operating rod, and operable by the signaller, and means whereby rotational movement can be imparted to the operating rod for varying the position of the said arm after sliding movement has

been imparted to the operating rod through the agency of the trigger.

4. A signaling device as claimed in claim 1 and having in combination a slidable and rotatable operating rod arranged parallel with the push rods, a radial arm secured on the operating rod and adapted to actuate the push rods in sequence, a trigger mounted on the operating rod and operable by the signaller, a spring whereby rotational movement in one direction can be imparted to the operating rod for varying the position of the said arm, and means having a part responsive to sliding movement of the operating rod for controlling the rotational movement thereof.

5. A signaling device as claimed in claim 1 and having in combination a slidable and rotatable operating rod arranged parallel with the push rods, a radial arm secured on the operating rod and adapted to actuate the push rods in sequence, a trigger mounted on the operating rod and operable by the signaller, a spring whereby rotational movement can be imparted to the operating rod for varying the position of the said arm, a second arm secured on and serving to transmit the action of the spring to the operating rod, and a gate with which the said second arm cooperates to control the rotational movement of the operating rod.

6. A signaling device as claimed in claim 1 and having in combination a slidable and rotatable operating rod arranged parallel with the push rods, a radial arm secured on the operating rod and adapted to actuate the push rods in sequence, a trigger mounted on the operating rod and operable by the signaller, a spring whereby rotational movement can be imparted to the operating rod for varying the position of the said arm, a second arm secured on and serving to transmit the action of the spring to the operating rod, a gate with which the said second arm co-operates to control rotational movement of the operating rod, a pawl carried by the second arm and adapted to co-operate with the gate, and resetting means combined with the operating rod.

7. A signaling device as claimed in claim 1 and having in combination a slidable and rotatable operating rod arranged parallel with the push rods, a radial arm secured on the operating rod and adapted to actuate the push rods in sequence, a trigger mounted on the operating rod and operable by the signaller, a spring whereby rotational movement can be imparted to the operating rod for varying the position of the said arm, a second arm secured on and serving to transmit the action of the spring to the operating rod, a gate with which the said second arm co-operates to control rotational movement of the operating rod, a pawl carried by the second arm and adapted to co-operate with the gate, resetting means combined with the operating rod, and means for adjusting the amount of rotational movement that can be imparted to the operating rod.

ARTHUR CYRIL WEBB ALDIS.
